CIRCUIT INTERRUPTER

Karl C. Randall, Edgewood, Pa., assignor to Westinghouse Electric & Manufacturing Company, East Pittsburgh, Pa., a corporation of Pennsylvania

Application June 28, 1940, Serial No. 342,924

19 Claims. (Cl. 200—162)

My invention relates generally to electric circuit interrupting devices, and more particularly to such devices embodying separable contacts, such as disconnecting switches.

It has been found that instead of attempting to obtain perfectly flat contact surfaces of substantial area in devices of this type, that at least as good, and in most cases better electrical contact may be obtained when using the same total pressures, by limiting the contact area and thereby raising the pressure per unit of contact area and providing more intimate engagement of the contacting surfaces. This principle is well recognized and has been embodied in conventional switch apparatus as shown, for example, in the patent to Herbert J. Crabbs, No. 2,208,411, issued July 16, 1940, and assigned to the assignee of this application. Such switch structures, however, have considerable contact friction at least for a portion of the movement of the switch. If contact portions of a noble metal having high conductivity are used, the rubbing of the contact portions under relatively high pressure is undesirable particularly when a relatively soft metal, such as silver, is used.

Accordingly, one object of my invention is to provide a novel circuit interrupter including high pressure, limited area separable contact portions, wherein substantially no sliding friction of the contacting portions occurs.

Another object of my invention is to provide a circuit interrupting device with novel limited area, high pressure, substantially self-freeing separable contact portions.

Another object of my invention is to provide a circuit interrupting device with novel pressure, separable contact means.

Another object of my invention is to provide a circuit interrupter having independently mounted separable contacts, which contacts embody self-aligning interengaging contact portions.

Another object of my invention is to provide a circuit interrupter embodying separable contacts, with novel operating means for causing high pressure engagement of said contacts.

These and other objects of my invention will become more apparent upon consideration of the following detailed description of preferred embodiments thereof, when taken in connection with the accompanying drawings, in which:

Figure 1 is a side view of a disconnecting switch embodying my invention with the switch shown in its fully closed position, and with portions of the insulator supports broken away;

Fig. 2 is a side view of the disconnecting switch shown in Fig. 1 with the switch illustrated in a partially closed position;

Fig. 3 is a top view of the disconnecting switch shown in Figs. 1 and 2 with the switch in the closed position shown in Fig. 1;

Fig. 4 is a side elevational view of a disconnecting switch illustrating another form of my invention with the switch in a fully closed position, and with portions of the insulator supports broken away; and

Fig. 5 is a fragmentary longitudinal sectional view illustrating a contact construction, some of the features of which may be used in connection with the disconnecting switches shown in Figs. 1 to 4.

Referring to Figs. 1 to 3 of the drawings, I have shown a switch which includes a pair of spaced supporting insulators 2 and 4. The insulators 2 and 4 may be of conventional design and are preferably made of porcelain, glass, or any other desired insulating material. As shown in Fig. 2, the insulators 2 and 4 may be secured to a supporting plate 6 as, for example, by the bolts 8. The insulator 4 supports a hinge contact construction which includes a contact support 10, secured to the insulator cap 9 as, for example, by the bolts 18. At the end of the contact support 10 adjacent the insulator 2, I provide a contact supporting flange 12 integral with the support 10, and spaced therefrom, I provide a second contact supporting flange 14 also integral with the base 10. The base 10 and supporting flanges 12 and 14 may be made of any desired conducting material such, for example, as copper or a copper alloy. The supporting flange 12, as shown, is relatively thin in order to provide for some flexibility and resiliency thereof. The contact support 10 further includes an integral extension 16 which extends outwardly of the insulator 4 to provide a terminal portion for connection of a line conductor thereto. The supporting flange 14 is provided with integral outwardly extending spaced pivot supporting arms 20 for pivotally supporting the switch blade 42 as will be hereinafter further described. The contact supporting flanges 12 and 14 have fixedly secured thereto opposite ends of a contact base member 22 which may be made of any desired conducting flexible and resilient material such, for example, as a copper alloy. The contact base 22 is in the form of an elongated strip, as shown in Fig. 3, having its opposite ends secured to the upper end of the supporting flange 12, and to the supporting flange 14 between the pivot sup-

porting arms 20, respectively. The ends of the contact base 28 may be secured to the supporting flanges 12 and 14 in any desired manner, such, for example, as by welding. Intermediate the ends of the contact base 22 I provide spaced, transversely extending projecting contact portions 24. As shown in Figs. 1 and 2, the contacting portions 24 have the opposite sides thereof convex in shape for a purpose hereinafter to be described.

The other insulator 2 likewise has secured to the cap 27 thereof, as by bolts 26, a contact supporting base member 28. The contact support 28 is provided with an integral supporting flange 30 at one end thereof, and a second integral supporting flange 32 spaced from the flange 30. The support 28 further includes a terminal extension 34 similar to the extension 16 on the contact support 18. The supporting flange 32 is provided with spaced locking extensions 36 adapted to cooperate with the switch operating means to lock the same in a closed position. The supporting flanges 30 and 32 support a contact base strip 38 of a flexible and resilient conducting material like the contact base 22. However, the contact base 38 is secured solely to the supporting flange 32 between the locking extensions 36 in a fixed manner, such, for example, as by welding or the like, and the other end of the contact base 38 is adapted to rest freely on the upper edge of the supporting flange 30. The contact base 38, like the base 22, is provided with spaced transversely extending contact projections 40 having the outer sides thereof of convex formation.

A switch blade 42 is provided for bridging the contact members provided on the insulators 2 and 4, respectively, and as shown, the blade 42 is provided with an enlarged aperture 44 at one end thereof adapted to be pivotally mounted on a pivot pin 46 extending through the aperture 44 in the blade, and through apertures in the spaced pivot supporting arms 20. As is apparent from Fig. 1, the aperture 44 is considerably larger than the cross section of the pivot pin 46 to allow for limited movement in a plane laterally of the insulators 2 and 4 for a purpose to be hereinafter described. The blade 42 is provided with laterally extending contact projections 48 and 50 adjacent opposite ends thereof, the contact projections 48 and 50, like the projections 24 and 40, are also provided with convex opposed side walls. An operating handle 52 is pivotally mounted at the free end of the blade 42 as by the pivot pin 56. As is more apparent from Fig. 3, the operating handle 52 may comprise a pair of strap members, welded, or otherwise secured together for the major portion of their length, with adjacent end portions thereof offset, as at 54, to be positioned at opposite sides of the switch blade 42 for pivotal connection with the outer ends of the pivot pin 56. The locking extensions 36 on the supporting flange 32 are provided with laterally extending cam arms 58, having lower cam surfaces 60 terminating in a locking indentation 62 adjacent the locking extensions 36. The cam surfaces 60 are formed to gradually approach the contact projections 40 towards the inner ends thereof, and their outer ends are formed with sharply upwardly curved portions 61. The cam surfaces 60 are adapted to cooperate with a cam follower in the form of a roller 64 mounted on the operating handle 52. As shown, the operating handle 52 has the outer end thereof formed with an annular portion 66 to form a hook-eye

for the reception of a hookstick operating member, or the like.

In the operation of the disconnecting switch shown in Figs. 1 to 3, the structure of which has 5 been described above, assuming the switch to be in a fully opened position, in order to close the switch it is first moved to substantially the position shown in Fig. 2. When the switch is fully 10 opened and the contact projections 48 and 50 on the blade 42 are entirely out of engagement with respect to the contact projections 24 and 40, the contact supporting bases 22 and 38, due to their inherent resiliency, will normally assume a substantially straightened position, such as the position 15 shown in Fig. 2 for the contact base 38. As the switch blade is moved by the operating handle 52 towards the closed position, the contact projection 48 will first engage between the contact projections 24 on the insulator 4. In 20 this form of my invention, I prefer to make the contact projections 48 and 50 on the blade 42 of a size to freely fit between the projections 24 and 40, respectively, when the contact bases 22 and 38 are in a straightened condition. Therefore, 25 when the switch is moved towards its closed position, the contact projection 48 on the switch blade will first substantially freely enter between the projections 24 on the contact base 22 to engage the portion of the base 22 between the 30 projections 24, and upon continued movement of the blade 42 in a counterclockwise direction, as seen in Figs. 1 and 2, the contact base 22 and supporting flange 12 may be flexed to the position shown in Fig. 2. The contact projections 35 48 and 24 engage prior to engagement of the projections 40 and 50 because the end of the blade adjacent the pivot 46 necessarily moves a smaller distance than does the outer end of the blade carrying the projection 50. The primary engagement of contact projections 24 and 48 is not 40 objectionable, however, in view of the extremely long lever arm between the operating handle pivot 52 and blade pivot 46, as compared to the small lever arm between the pivot 46 and contact projection 48. Therefore, even though the 45 material of the contact base 22 is relatively stiff, flexure of this member to the position shown in Fig. 2 is relatively easily accomplished.

The next thing which occurs in the closing movement of the switch blade 42 is engagement of the blade contact projection 50 between the projections 40 on the contact base 38. This is the position shown in Fig. 2 of the drawings, and continued movement of the operating handle 52 in a counterclockwise direction from the position shown in Fig. 2 results in relative pivotal movement of the operating handle with respect to the blade 42 about pivot 56, with the cam roller 64 on the handle in engagement with the cam surface 60 on the cam arms 58. This movement results in the application of pressure to the outer end of the switch blade 42, causing a slight further downward movement of the projection 48, and considerable downward movement 55 of the projection 50 on the switch blade to the position shown in Fig. 1, when the cam roller 64 is seated in the locking indentation 62, to effectively lock the switch blade in this position. The considerable downward movement of the outer end of the blade 42 causes the contact projection 50 to flex the contact base 38 in a substantially arcuate manner, as clearly shown 60 in Fig. 1.

I desire to again particularly point out that the contact projections 48 and 50 are of a size

in relation to the spacing of the contact projections 24 and 40, so that when the contact bases 22 and 38 are in a straightened condition, the projections 48 and 50 may freely enter between the contacts 24 and 40, respectively. In the straightened condition of the contact bases 22 and 38, the contact projections 24 and 40 are designed to extend substantially laterally or perpendicularly with respect to the contact bases 22 and 38. Now when the bases are flexed to the positions shown in Fig. 1 in an arcuate manner, obviously the projections 24 and 40 being integral with the bases 22 and 38, respectively, will maintain their normal relation with respect to the bases and hence will extend substantially radially with respect to the curvature of the bases, and therefore will have their outer ends moved inwardly towards each other. This will press outer portions of the contact projections 24 and 40 into engagement with the outer sides of the blade projections 48 and 50, respectively. Obviously, the pressure of this engagement can easily be made quite high because of the advantageous high ratio of the distance between the center of each contact base and its end supports, as compared to the height of a contact projection supported thereon. I also desire to point out that this high pressure engagement of the contact projection will be substantially along a line extending longitudinally of the projections, or laterally with respect to the blade and contact supports 22 and 38, inasmuch as the contacting surfaces of the projections are outwardly convex.

It should be noted that in the closing movement of the switch, any disalignment of projection 48 with respect to projections 24 due to manufacturing or assembling inaccuracies will be compensated for by the loose pivotal connection 44, 46 of the switch blade, to permit the projection 48 on the blade to locate itself between the contact projections 24. Also, any disalignment of the blade contact projection 50 with respect to the contact projections 40 will be compensated for by the particular mounting of the contact base 38. As shown, the contact projections 49 and 50 have outer convex surfaces so that when brought into engagement, any slight disalignment will tend to provide the projection 50 with a camming effect on one or the other of projections 40, to flex the contact base 38 which is capable of considerable movement in view of the free method of supporting one end thereof on the supporting flange 39.

When it is desired to move the switch from the position shown in Fig. 1 to an open position, it is merely necessary to move the operating handle 52 in a clockwise direction as viewed in Fig. 1, and after movement of the cam roller 64 on the operating handle 52 from the locking indentation 62 on the cam arms 58, the contact projections are adapted to free themselves from the high pressure engagement shown in Fig. 1, due to the resiliency of the contact bases 22 and 38 which, having been stressed to the positions shown in Fig. 1, will automatically restore themselves to straightened positions such, for example, as the straightened position of the base 38 shown in Fig. 2. This not only operates to move the switch blade 42 in a clockwise direction upwardly from the position shown in Fig. 1, but also operates to separate the contact projections 24 and 40 to thereby free the blade projections 48 and 50 so that the entire opening movement of the blade is substantially friction-

less, at least being unopposed by any contact friction. This is an important feature of my invention, especially if a noble metal such as silver, or the like, is used on the contacting surfaces of the contact projections, inasmuch as such materials have certain disadvantages when in high pressure frictional engagement. It should also be noted that the contacting pressures obtained between the contact projections in the closed position of the switch may be predetermined by the resilient properties of the contact supports 22 and 38, respectively, and may be made at any desired value up to a high value determined by the strength of the materials employed.

Referring to Fig. 4, I have shown another form of disconnecting switch embodying certain principles of my invention, and inasmuch as certain parts of this switch are the same as corresponding parts of the switch shown in Figs. 1 to 3 of the drawings, like reference numerals will be used to designate such parts. As shown in Fig. 4, the insulator 4 in this embodiment of my invention has secured to its end cap 9, a contact supporting plate 70 having a terminal extension 72 for the connection thereto of the line conductor. The supporting plate 70 is provided with a central, integral, elongated projecting contact base 74, for supporting a pair of contact spaced projections 76. The contact projections 76 have opposed contacting side walls, with the curvature of the inner facing walls of the projections being arranged so that a slot is formed between the projections with the walls of the slot arcuately flaring outwardly.

The insulator 2 similarly, has secured to its end cap 27 a contact base 78 provided with a terminal extension 80. The contact base 78 is provided with spaced opposed supporting flanges 82 and 86, each of which is provided with facing arcuate supporting surfaces 84 and 88, respectively, which surfaces are in the form of reverse curves curves with the lower portions of such surfaces being closer together than the upper portions thereof. The supporting flange 86 is provided with a central pivot supporting flange 90 integral therewith, and extending toward the supporting flange 82 for pivotally supporting the contact base member 96. The contact base member 96 is provided with a slot for receiving the flange 90, and a pivot pin 92 is adapted to be passed through the contact base 96 and through an enlarged aperture in the pivot supporting flange 90 for loosely pivotally connecting the contact base 96 with the supported flange 90. As shown, the contact base 96 is provided with curved ends 97 adapted to be seated on the outer portions of the curved supporting walls 84 and 88, respectively, of the supporting flanges 82 and 86. The sole connection of the contact base 96 with the contact support 78 and its supporting flanges is by means of the pivot pin 92 fitting loosely in the pivot aperture 94. A coiled compression spring 98 is provided between the contact base 96 and the contact support 78, with the ends thereof seated in suitable recesses in these parts to locate the same. In the position shown in Fig. 4 the coil spring 98 is compressed so that when the switch is open the contact base 96 will be moved by the spring 98 to the dotted line position shown in Fig. 4, into engagement with the stop lug 100 formed on the spaced locking extensions 104 integral with the supporting flange 82. The contact base 96 is also provided with a pair of spaced contact projections 102 similar in

construction to the projections 76, previously described.

The switch blade 106 in this embodiment of my invention is movably connected to the contact base 74 by means of a pair of pivot links 108 (only one of which is shown) having opposite ends thereof pivotally connected to the blade 106 and contact base 74, by pivot pins 112 and 110, respectively. The pivot pin 110 connecting the links 108 to the contact base 74 is received in a slot 109 formed in an extension of the base 74, and is normally maintained in the lower end of the slot 109 by a coil compression spring 111 located between the pivot pin 110 and one end of slot 109, for a purpose to be hereinafter referred to. The blade 106 is provided with contact projections 114 and 116 adapted to engage between the contact projections 76 and 102, respectively, in the closed position of the switch. The blade is further provided with an operating handle 52, like that described in Figs. 1 to 3 of the drawings, and which is adapted to lock the switch blade in its closed position in the same manner previously described, and, therefore, the structure and function of these parts will not be repeated.

In the operation of the switch disclosed in Fig. 4, assuming the switch to be in the fully open position, the contact support 96 will then be in a position corresponding to the dotted line position shown in Fig. 4 in engagement with the stop lug 103. Now upon movement of the switch blade in a counterclockwise direction to close the switch the link connection 108 of the blade to the contact base 74 permits movement of the blade laterally relative to the contact projections 76 to enable the projection 114 to be self-aligning with respect to the contact projections 76, and engagement of blade contact projection 116 with the contact projections 102 by virtue of the resiliently biased relatively loose pivotal support of the contact base 96 will enable the blade contact projection 116 to move the projections 102 and consequently the contact base 96 to an aligned position, to thereby account for any possible disalignments due to manufacturing or assembling inaccuracies in these switch parts. As the switch is moved to its fully closed position and pressure is applied to the blade by cooperation of the cam roller 64 with the cam surface 60, the blade contact projections 114 and 116 come into relatively high pressure engagement with the contact projections 76 and 102, respectively. In this embodiment of my invention, in closing the switch the contact projections 116 and 102 will engage first to automatically align these parts, and move the contact base 96 from the dotted line position shown in Fig. 4 substantially to the full line position before the blade contact projection 114 engages the fixed contact projections 76. Further movement in the closing direction of the blade 106 results in high pressure engagement of the contact projections and also acts to force the contact base 96 into intimate conductive engagement with the supporting surfaces 84 and 88 on the supporting flanges 82 and 86, respectively, and also compresses the coiled compression spring 98. Any vertical disalignment of the insulators 2 and 4, and consequently of the contacts 76 and 102, is taken care of by the resilient support for pivot pin 110 of the switch blade 106. In other words, if the contact projections 76 are in a plane above the contact projections 102, these contacts will be engaged first, and the blade will pivot about its contact projection 114 to engage its contact projection 116 with the projections 102. This

5 pivotal movement about the plate contact projection 114 is permitted by movement of the pivot pin 110 upwardly in slot 109 against the force exerted by the spring 111. The contact supporting parts 70 and 74 are preferably of a size to support contact projections 76 slightly outwardly of the plane of contact projections 102 so as to insure high pressure engagement of contact projections 102 and 116.

10 Opening movement of the switch in this embodiment of my invention is also resiliently aided by the spring 98. The coiled compression spring 98 when the switch blade is opened, also aids in freeing the contact projections 76 and 114 15 from the blade contact projections, and furthermore, because of relative tilting movement between the switch contact base 96 and the switch blade 106 and hence between the contact projections 102 and 116 during switch opening 20 movement, also has the function of freeing these contact projections, so that it is apparent I have also provided in this embodiment of my invention, substantially self-freeing contacts.

25 It should be noted that the contact projections 114 and 116 on the switch blade in this embodiment of my invention are made to be substantially wider than the bottom portion of the slot formed between the contact projections 76 and 102, respectively. Therefore, the projections 30 114 and 116 are not permitted to penetrate the full depth of the slot between the contact projections 76 and 102, so that the convex side walls of these projections engage with substantially line contact portions at points spaced above 35 the contact bases 96 and 74. This contact construction provides for substantially a wedging action upon engagement of the switch contact portions.

40 In Fig. 5 of the drawings, I have illustrated 40 a contact construction including a contact base 118 which may be supported in the same manner as the contact bases 22 and 38 shown in Figs. 1 to 3 of the drawings. I have also shown inter-engaging contact projections 128 and 120 which 45 are capable of use either with the switch in Figs. 1 to 3 of the drawings or with the switch shown in Fig. 5. The contact base 118 in this embodiment of my invention, however, may have little, if any, resiliency and is preferably relatively thin 50 and flexible, and may be of any suitable flexible conducting material, such for example, as a relatively thin copper strap. Inasmuch as the base 118 has little or no resiliency, a coiled compression spring 124 is provided between the contact 55 support 122 and the base 118 for returning the base to substantially a straightened position when the switch is open. When the switch is closed, of course, the base may be arcuately flexed in the manner shown in Fig. 5 to bring 60 the contact projections 120 integral with the base into high pressure engagement laterally with the contact projection 128 formed on the switch blade 126. The configuration of the contact projections in this embodiment of my invention is 65 similar to that of the projections described in connection with the embodiment shown in Fig. 4. However, Fig. 5 being on an enlarged scale, the line contact of the projection is more readily apparent at the corners 130 of the blade contact projection 128. As shown in Fig. 5, the contact projections 128 and 120 are provided with a coating 132 of low resistance material such, for example, as a noble metal, such as silver or the like, to provide contacting surfaces which will be substantially non-corrosive and

resistant to deterioration. Obviously, if desired, this coating or layer may be confined solely to the contacting surfaces of the contact projections rather than being on all exposed surfaces of these projections.

The operation of the contacts in opening and closing an interrupter in accordance with the construction shown in Fig. 5 is very similar to the operation of the switches previously described and, therefore, this operation will not be recited in detail. It is thought sufficient to state that limited area high pressure contact is obtained without employing any contact friction. It is believed obvious that this contact construction will be self-freeing in the same manner as the contact construction shown in Figs. 1 to 3 of the drawings. This construction has the advantage that none of the current carrying parts is required to be of a resilient material, inasmuch as the spring 124 may be of a high resistant material and does not necessarily carry current.

From the foregoing, it is believed to be apparent that I have particularly disclosed certain forms of disconnecting switches, constructed in accordance with my invention, which feature in general, limited area, high pressure, self-aligning separable contacting portions, without resorting to any sliding friction on the contacts, and wherein the contacts on all forms of switches disclosed are self-freeing from their high pressure engagement. It should also be noted that I have provided in circuit interrupters embodying interfitting separable contacts, means to compensate for any disalignment of the interfitting parts which might be occasioned by manufacturing or assembling inaccuracies so that careful and extensive machining of such parts is not required, rendering it possible to economically construct a switch of this type. The switches disclosed are also provided with a novel construction and arrangement of parts for obtaining high pressure engagement of separable switch contacts and these, as well as numerous other novel features disclosed, are all intended to be comprehended as parts of my invention.

Having described preferred embodiments of my invention in accordance with the patent statutes, I desire it to be understood that my invention is not limited to the particular structures disclosed herein, inasmuch as it will be obvious, particularly to persons skilled in the art, that many changes and modifications may be made in these structures without departing from the broad spirit and scope of my invention. Therefore, I desire that my invention be interpreted as broadly as possible and that it be limited only by what is expressly stated in the following claims.

I claim as my invention:

1. In a circuit interrupter including separable contact means, the combination wherein one of said contact means includes a flexible supporting member supported at spaced points and having spaced relatively rigid contact projections fixed thereto intermediate said supporting points, and the other of said contact means includes a cooperating contact projection adapted to be received between said first mentioned projections to flex said supporting member and provide high pressure lateral engagement of said projections.

2. In a circuit interrupter including separable contact means, the combination wherein one of said contact means includes a flexible and resilient supporting member supported at spaced

points and having spaced relatively rigid contact projections fixed thereto intermediate said supporting points, and the other of said contact means includes a cooperating contact projection adapted to be received between said first mentioned projections to flex said supporting member and provide high pressure lateral engagement of said projections.

3. In a circuit interrupter including separable contact means, the combination wherein one of said contact means includes a flexible supporting member supported at spaced points and having spaced relatively rigid contact projections fixed thereto intermediate said supporting points, and the other of said contact means includes a cooperating contact projection adapted to be received between said first mentioned projections to flex said supporting member and provide high pressure lateral engagement of said projections, and biasing means opposing said flexing movement of said supporting member.

4. In a circuit interrupter, a contact member including a projecting contact portion mounted for movement into and out of engagement with respect to a cooperating contact, said cooperating contact including spaced relatively rigid contact portions adapted to receive said projecting contact portion therebetween and a flexible supporting base member fixedly supported at spaced points and carrying said spaced contact portions intermediate said supporting points, said supporting base member normally assuming an unflexed position when said interrupter is open, so as to be flexed by said contact member in the closed position of said interrupter to cause said spaced contact portions to laterally engage said projecting contact portion under pressure.

5. In a circuit interrupter, a contact member including a projecting contact portion mounted for movement in a fixed path into and out of engagement with respect to a cooperating contact, said cooperating contact including a relatively rigid projecting contact part positioned to be closely adjacent one side of said contact projection in the closed position of said interrupter, and a flexible supporting member supported at spaced points and rigidly carrying said contact part intermediate said supporting points so that said contact part is moved laterally into engagement with said contact projection upon pressure engagement of said contact member and supporting member at a point intermediate said spaced points.

6. In a circuit interrupter, a contact member including a projecting contact portion mounted for movement into and out of engagement with respect to a cooperating contact, said cooperating contact including spaced relatively rigid projecting contact portions adapted to receive said projecting contact portion therebetween and a flexible supporting base member supported at spaced points and fixedly carrying said spaced contact portions intermediate said supporting points, said supporting base normally assuming an unflexed position when said interrupter is open, so as to be flexed by said contact member in the closed position of said interrupter to cause said spaced contact portions to laterally engage said projecting contact portion under pressure, and said supporting base being resiliently biased to said normal position whereby to freely release said projecting contact portion upon movement thereof out of engagement with respect to said cooperating contact.

7. In a circuit interrupter, a contact member

including a projecting contact portion mounted for movement in a fixed path into and out of engagement with respect to a cooperating contact, said cooperating contact including a relatively rigid contact part positioned to be closely adjacent one side of said contact projection in the closed position of said interrupter, and said cooperating contact means further including a flexible support member rigidly carrying said contact part and which is supported at a point spaced on the opposite side of said contact part from the point of engagement of said contact portion whereby, upon pressure engagement of said contact member and contact means, at least a portion of said contact part is moved laterally into pressure engagement with said contact projection.

8. A contact member including a flexible base member adapted to be supported at spaced points, and relatively rigid, spaced projecting contact portions integral with a portion thereof intermediate said spaced points.

9. A contact member, including a flexible base member, intermediate, spaced, laterally extended opposed contact portions rigid with said base member, spaced supporting means for said base member, at least one of which is fixedly secured to said base member to permit flexure thereof.

10. A contact member including a flexible base member, intermediate, spaced, laterally extending contact portions rigid with said base member, spaced supporting means for said base member one of which is fixedly secured to said base member, and the other of which movably supports a spaced part of said base member to permit flexure thereof.

11. A contact member, including a flexible base member, intermediate, spaced, laterally extending opposed contact portions rigid with said base member, spaced supporting means for said base member at least one of which is of flexible material, and both of said supporting means being fixedly secured to said base member to permit flexure thereof.

12. In a circuit interrupter, separable contact means at least one of which is mounted for movement into and out of engagement with respect to the other of said contact means, said contact means including base members with interfitting substantially tongue and groove contacting portions fixed on said base members, respectively, and with the groove extending at an angle to the plane of movement of said one contact and adapted to provide limited area high pressure contact in the closed position of said interrupter, and one of said base members being mounted for movement substantially laterally of said first movement to compensate for any disalignment of said contacting portions.

13. In a circuit interrupter, separable contact means at least one of which is mounted for movement into and out of engagement with respect to the other of said contact means, said contact means including base members with interfitting substantially tongue and groove contacting portions extending at an angle to the plane of movement of said one contact and adapted to provide limited area high pressure contact in the closed position of said interrupter, and said one of said base members being mounted for movement substantially laterally of said first movement to compensate for any disalignment of said contacting portions.

14. In a circuit interrupter, spaced contacts, and a bridging contact mounted for movement

5 into and out of engagement with respect to said spaced contacts, said contacts including interfitting substantially tongue and groove contacting portions with the groove extending at an angle to the plane of movement of said one contact and adapted to provide limited area high pressure contact in the closed position of said interrupter, said bridging contact being also mounted for lateral movement with respect to said spaced contacts to accommodate any disalignment in at least one of said spaced contacts, and one of said spaced contacts being movable toward and away from the other of said spaced contacts to compensate for non-uniform spacing of said contacting portions.

15. In a circuit interrupter, separable contact means at least one of which is mounted for movement into and out of engagement with respect to the other of said contact means, said contact means including limited area contacting portions, operating means movably associated with said movable contact means, and relatively fixed pressure applying means positioned to cooperate with said operating means adjacent the closed position of said interrupter to apply pressure to said contacting portions by relative movement of said operating means with respect to said movable contact means.

16. In a circuit interrupter, separable contact means at least one of which is mounted for movement into and out of engagement with respect to the other of said contact means, said contact means including limited area contacting portions, operating means movably associated with said movable contact means, and pressure applying means positioned to cooperate with said operating means adjacent the closed position of said interrupter to apply pressure to said contacting portions by relative movement of said operating means with respect to said movable contact means, and means for locking said interrupter in a closed position with said contacting portions in high pressure engagement.

17. A contact member including a flexible base member adapted to be supported at spaced points, and spaced, rigid projecting contact portions fixed to portions of said base member intermediate said spaced points.

18. In a self-aligning contact structure, a floating contact member loosely pivotally mounted adjacent one end thereof for pivotal movement about said one end and for limited movement laterally of said pivot axis, and means for biasing said contact member for movement in a direction generally towards a cooperating contact member.

19. In a circuit interrupter including separable contact means, the combination wherein one of said contact means includes a flexible supporting member having spaced, rigid contact projections fixed thereto, the other of said contact means including a cooperating contact projection adapted to be received between said first mentioned projections, actuating means movably mounted on said other contact means for moving said contact projection of said other contact means into and out of a position between said spaced contact projections, and force-multiplying means operative in response to relative movement of said actuating means when said cooperating contact projection is in said position between said spaced contact projections to flex said supporting portion and provide high pressure lateral engagement of said projections.

KARL C. RANDALL.
